MULTIPLE CONDIMENT HOLDER

Adrienne Brita Juvet Dokus and John Ivan
Dokus, Newark, N. J.

Application June 24, 1949, Serial No. 3,507

Term of patent 14 years

(Cl. D44—22)

To all whom it may concern:

Be it known that we, Adrienne Brita Juvet Dokus and John Ivan Dokus, citizens of the United States of America, residing at Newark, in the county of Essex and State of New Jersey, have invented a new, original, and ornamental Design for Multiple Condiment Holder, of which the following is a specification, reference being had to the accompanying drawing, forming a part hereof.

In the drawing:

Figs. 1 and 5 are side perspective views of a multiple condiment holder, showing our new design;

Fig. 2 is a front perspective view; and

Figs. 3 and 4 are respectively top and bottom plan views thereof.

We claim:

The ornamental design for a multiple condiment holder, substantially as shown.

ADRIENNE BRITA JUVET DOKUS.
JOHN IVAN DOKUS.
